UNITED STATES PATENT OFFICE

117,210

DESIGN FOR A CAN OPENER

Myron J. Zimmer, Chicago, Ill., assignor to The
Edward Katzinger Company, Chicago, Ill., a
corporation of Illinois

Application January 24, 1938, Serial No. 74,499

Term of patent 14 years

To all whom it may concern:

Be it known that Myron J. Zimmer, a citizen of the United States, residing at Chicago, in the county of Cook and State of Illinois, has invented a new, original, and ornamental Design for a Can Opener, of which the following is a specification, reference being had to the accompanying drawing, forming part thereof.

Fig. 1 is a plan view of a can opener, with the cork screw element retracted, showing my new design;

Fig. 2 is a perspective view thereof with the cork screw element extended.

The dominant feature of my design resides in the formation of the oppositely longitudinal edges of the arms of the handle and the joining of said arms at the rearward end of the handle by an arcuate portion of a diameter exceeding the distance between said arms.

I claim:

The ornamental design for a can opener, as shown and described.

MYRON J. ZIMMER.
